WATCH AND JEWELERS' VISE

Charles B. Greenberg, New York, N. Y.

Application September 9, 1942, Serial No. 457,727

2 Claims. (Cl. 81—6)

My invention relates to vises and in more detail to a precision type of watch vise suitable for gripping and holding firmly yet lightly small and delicate elements such as watch parts.

An object of my invention is to design a type of jeweler's watch vise in which both jaws are slidably mounted. Another object is to form the chucks with shaped sections and overhanging lips in order to grip firmly a variety of forms. A third object is to mount the chucks in a manner which will minimize play in the gripping elements. A fourth object is to form a vise in which there are three separate places of contact between the chucks and the base. A fifth object is to design a simple, inexpensive and easily assembled vise requiring no welding, freezing or soldering of parts.

I accomplish these and other objects by forming my watch vise with a base part provided with double seated angled groove guideways, two opposingly female threaded chucks, having wedged and shaped lugs suitable for gripping and also provided with angled guides extending into and carried by the guideways of the base part and a shaft opposingly threaded at each end to function with the chucks and centrally enlarged to rest in and be retained in and guided by a cross bar secured to the base part.

In the drawing Fig. 1 shows a plan view of my vise, Fig. 2 shows a side view in the direction of the axis of the shaft of the vise, Fig. 3 shows a side view in a direction perpendicular to the axis of the vise shaft and Fig. 4 shows an enlarged detail of the shaft, cross bar and part of a chuck.

Referring now to the drawing, in which similar numbers represent corresponding elements, the vise, in general, is designated by 1, the base 2, and the chucks 3 and 4, respectively.

The base 1 is formed of a circular ring under-part 5 supporting an upper part of two shoulder elements 6 each having upper faces 7, and opposing side faces 8. The opposing faces 8 of the shoulders are each provided with an angled section 9, horizontal seat 10 and vertical section 11, which form a guideway to carry the chucks 3 and 4.

In order to reduce the play of and hold the chucks 3 and 4 in the guideway they are each provided at their lower extremities with the under face 12, angled section 13, and the raised under face 14 complementary respectively to and functioning against their corresponding guideway parts, the horizontal seat 10, angled section 9, and upper face 7. The upper extremities of

the chucks are provided, in a direction perpendicular to their travel, with the straight sides 16 and the arcuate sides 17 both of which are provided with the under cut gripping shoulders or lugs. In addition an indenture 18 is provided so that a watch can be held flat or level even though the crown has not been removed.

So that the vise can be operated speedily the two chucks are provided, at about their mid sections and in the direction of their travel, with opposingly female threadings 19 to carry a shaft 20.

The shaft 20 is appropriately threaded to carry and function with the chucks 3 and 4, one at each end. To increase the stability of the moving elements and reduce the play in the chucks to a minimum there is provided at the center of the shaft an enlarged section or flange 23 which rests in an opening 24 in the cradle 25 of the cross bar or strap 26. The cross bar or strap 26 extends across the opening between the opposing faces 8 of the upper part of the base and is secured to the under part of the base by the screws 27.

A variation in the details of construction can be made by providing a flange on or in the cradle and a reduced portion in the shaft to carry the flange. Also, instead of a cradle, the cross bar can be built up about the sides of the shaft and the same results are obtained as by the flange 23 resting in the opening 24 in the cradle 25 of the cross bar.

In order that the opposing faces 21 of the chuck can travel beyond and close over the cross bar and the enlarged center flange of the shaft the faces are provided at the position of the threadings with the cut out or enlarged openings 22. In order to easily operate the chucks the ends of the shaft are provided with the knurled enlarged heads 28.

Although I have only shown and described my vise in its main form, several variations are possible without departing from the spirit and scope of the ideas conveyed in the drawing and descriptions, and so I desire to cover all modifications, forms or embodiments of my invention coming within the scope and language of any and all claims.

I claim:

1. A watch vise comprising a base part, two opposing chuck elements partly resting and functioning in the base part and a chuck motivating shaft means having an enlarged flanged portion at its center, the base part being provided with an angled shouldered guideway, the chuck ele-

ments being provided with seating portions to function in the guideway and opposing gripping faces to hold objects and each chuck opposingly female threaded to co-act with the chuck motivating shaft and a strap attached at each end to and extending across the base part and said strap provided with a cradle section aligned with the shaft and having an opening therein into which the enlarged flanged portion of the shaft means rests and by which the shaft is held from movement in an axial direction.

2. A watch vise comprising a base part, two opposing chuck elements partly resting and functioning in the base part and a chuck motivating shaft means, the base part being provided with an angled shouldered guideway, the chuck ele-

ments being provided with seating portions to function in the guideways and opposingly gripping faces to hold objects and each chuck opposingly female threaded to co-act with the 5 chuck motivating shaft and a cross bar in the base part provided with a cradle having a recessed portion therein, and a flange on said shaft, said cradle and recessed portion functioning with the flange to limit the play in and guide the movement of the shaft, and the chucks provided with cut out portions in their opposing parts about their threadings of such a size as to permit the chucks to close over the cross bar and contact each other.

CHARLES B. GREENBERG.
